BUILDING WALL

Joseph Banneyer, Chicago, Ill.

Application May 26, 1950, Serial No. 164,571

3 Claims. (Cl. 72—17)

This invention relates to a building wall, and is particularly useful in the construction of a house or building through the use of building blocks, tile and the like.

An object of the invention is to provide a wall structure providing an air space between the main wall and the inner wall and permitting, when desired, the circulation of air through said space. Yet another object is to provide building blocks providing for the ready attachment to the inner sides thereof of an inner wall and furnishing air channels for the circulation of air between the inner and main walls. A still further object is to provide building blocks equipped with interlocking means and means for anchoring furring strips thereto without the use of nails and the like. A still further object is to provide insulated blocks which may be placed upon each other in staggered relation to form a wall while providing interlocking recesses and means for securing the blocks together and for securing an inner wall in spaced relation to the blocks. Other specific objects and advantages will appear as the specification proceeds.

The invention is shown in illustrative embodiments, by the accompanying drawings, in which—

Fig. 1 is a broken side view in elevation of a wall embodying my invention; Fig. 2, a vertical sectional view, the section being taken as indicated at line 2—2 of Fig. 1; Fig. 3, a horizontal sectional view, the section being taken as indicated at line 3—3 of Fig. 1; Fig. 4, a horizontal sectional view, the section being taken as indicated at line 4—4 of Fig. 1; Fig. 5, a perspective view of one of the blocks which may be employed; Fig. 6, a perspective view of another form of block that may be used; Fig. 7, a transverse sectional detail view showing means for securing the furring strips to the wall and for interlocking the blocks in the wall; Fig. 8, a view of another portion of the wall that may be employed with the tier of blocks shown in Fig. 7; Fig. 9, a perspective view of the type of block shown in Fig. 4; Fig. 10, a perspective view of the block employed in the wall structure shown in Fig. 8; Fig. 11, a perspective view of a tie member; Fig. 12, a perspective view of another form of tie member; Fig. 13, a horizontal view of building blocks employed in connection with brick veneer; Fig. 14, a view similar to Fig. 13 but showing a modified form of structure; Fig. 15, a perspective view of a form of block shown in Fig. 13; and Fig. 16, a perspective view of a form of block employed in the wall structure shown in Fig. 14.

In the construction shown in Figs. 1 to 6 inclusive, a block unit 10 is employed in forming the tier illustrated in Fig. 3, while the block 11 is employed in the tier of blocks illustrated in Fig. 4. The wall structures 3 and 4 are superposed, as illustrated in Fig. 1, and the staggered relation is continued from the bottom of the wall to the top.

The block 10 is provided with rearwardly-extending projections 12 and 13 providing therebetween a space 14. On either side of the projections 13 are members defining the V recesses 15 and 16. Also, the ends of the blocks are notched to provide vertical V recesses 17. The body of the block 10 may be provided with vertical openings or channels 18 to provide insulating air spaces.

When a series of blocks 10 are brought together in a single tier, as illustrated in Fig. 3, the recesses 15 and 16 form a channel adapted to receive a furring strip 19, the furring strip having a dovetail locking portion 20. Also, the V notches or recesses 17 form a diamond-shaped space 21 between the blocks and this may be filled with con-

crete, cast material, metal members, or any other means for locking the two blocks together.

The corner member 22 may be cast in situ by using forms and the forms will provide the V-shaped recesses 5 similar to the recesses 15, 16 and 17 of the blocks. If desired, the corner members 22 may be formed by blocks which are placed in superposed relation.

The block 11, which is in a tier below or immediately above the tier shown in Fig. 3, is provided at its ends 10 with V recesses 23 and at its rear with projections 24 which provide between them a rectangular recess 25 adapted to receive the body of the furring strip 19. Since there is no dovetail recess provided, the furring strip 19 will have spaces between its dovetail portion 20 and the side walls 15 of the recess 25. If desired, these recesses may be filled with concrete 26 or with any other suitable material, or the spaces may be left open.

The block 11 is also provided with insulation spaces 27. When the blocks are brought together in a tier, as illustrated in Fig. 4, the recesses 25 receive the furring strips 19 and the V recesses 23 provide with the recesses of adjacent blocks diamond-shaped spaces for receiving cast material to interlock the blocks. Instead of cast material, metal members or any other suitable means for providing the interlock may be employed. The tier shown in Fig. 4 may also be provided with corner block members 28 and 29, as shown in Fig. 4; or, if desired, the corner portions may be cast as a pillar extending from the bottom to the top of the wall, suitable forms being provided for this purpose.

After the wall has been formed, as described in connection with Figs. 1, 3 and 4, a metal lath or board 30 may be attached to the inner side of the wall by nailing or stapling the wire to the furring strips 19. Plaster 31 may be applied over the metal lath 30, or any other structure for forming an inner wall may be provided. With the structure shown, there is a vertical channel 32 provided from the bottom to the top of the wall. In the tier shown in Fig. 3, each channel is provided for the tier by the space 14. In the tier shown in Fig. 4, a corresponding channel is provided at 33 by two adjacent blocks 11.

Any suitable type of floor and foundations may be provided. In the structure shown, I provide a concrete floor 34 carried by a foundation wall 35. The floor 34 is provided with an air space 36 which extends longitudinally of the floor and permits the flow of air from the basement upwardly through the space and preferably to the attic of the house. Similarly, cold air may flow from the attic downwardly through the space and into the basement area. The concrete floor 34 may be provided with reinforcing concrete beams 37 to provide a sturdy support for the space, and preferably the air space 36 extends over the beams and along each side of the floor.

In the modification shown in Fig. 7, the wall tier is formed by the use of blocks 38. These blocks are provided at their ends with two recesses 39 and 40. The recesses 39 may be filled with concrete or other fastening means to provide an interlock between the blocks.

The inner diamond-shaped recesses 40 may be employed for a new purpose. This recess is adapted to receive a tie member 43, as illustrated in Figs. 7 and 11. The diamond-shaped head of the tie member 43 fits within the recess 40 while the legs thereof are extended through the furring strip 44 and spread outwardly against the front face of the furring strip to secure it in position. It will be understood that, if desired, the furring strip 44 may be omitted and the corresponding part of the blocks 38 may be left without a recess, the legs of the tie member 43 being extended through and clenched behind the metal lath or building board.

A tie member 45, as shown in Figs. 7 and 12, may also be employed. The inner portion of the tie member is locked within the recess 40, while the leg portions are drawn around the furring strip 44 and bent inwardly to lock the furring strip in position.

The blocks in the tiers above and below the tier shown in Fig. 7 may be of the shape shown in Figs. 8 and 10. Here the blocks 46 are provided with V recesses 47 at their ends and have rearwardly-extending projections 48

providing a rectangular channel 49 for receiving the furring strip 44.

In the structure shown in Figs. 13, 14, 15 and 16, I provide blocks which are employed in connection with brick veneer. For example, in Fig. 13 I provide a block 50 which is adapted to be used in connection with the veneer formed of bricks 51. Similarly, I provide a block 52 (Fig. 16) which is particularly useful in connection with the brick veneer as illustrated in Fig. 14. The corner column 53, as shown in Fig. 13, may be cast of concrete and provided with the V grooves or recesses for interlocking with the hollow blocks, or, if desired, the column may be formed by the use of superposed blocks.

In the structure shown, there is provided a building wall which will permit the free and constant circulation of air for either cooling or heating purposes. Further, the wall provides recesses for furring strips to which the lath and plaster are attached. Also, if desired, the wall provides built-in fasteners which will either hold the furring strips or the wire lath or plaster board firmly in place, thus avoiding the expense and unsatisfactory construction resulting from the nailing of furring strips to brick or concrete walls. It will also be observed that the wall provided by the blocks as described provides dead air spaces as a result of the openings, such as 18 and 27, in the blocks, and also active air spaces as provided, for example, by the spaces 14 and 25 in the blocks, the blocks being arranged in staggered relation but with the active air spaces in vertical alignment so that air may pass freely in a vertical path between the main wall and the plaster or inner wall.

In pouring the corner columns 22 as hereinabove described, inner and outer forms may be used so that the concrete, as it flows downwardly, will move inwardly between the staggered ends of the blocks, thus forming a vertically-extending concrete column with the concrete extending on each side of those blocks which project inwardly into the column. Thus the column ties together the blocks and provides an anchor for them in the wall. If desired, the concrete column may be marked with block lines so as to give the wall an appearance of blocks extending uniformly along the wall.

While in the foregoing specification I have set forth specific structures in considerable detail, for the purpose of illustrating embodiments of the invention, such details of structure may be varied widely by those skilled in the art without departing from the spirit of my invention.

I claim:

1. In a building structure, superposed tiers of building blocks providing an outer wall in which the blocks therein are staggered horizontally for adjacent tiers and aligned vertically for alternate tiers, said tiers being of two types alternately arranged within said wall, one type of said alternate tiers being composed of blocks having vertically-extending notches at their inner ends forming enlarged spaces between the ends of the blocks for receiving furring strips extending vertically along the side face of said outer wall, the other type of said tiers being composed of blocks having vertically-extending recesses located intermediately in the inner faces of the blocks and providing furring strip receiving channels vertically aligned with said enlarged spaces, furring strips received within said recesses and said enlarged spaces so as to extend vertically along the inner face of said outer wall, an inner wall carried by said furring strips at a spaced distance from vertically aligned portions of the inner face of said outer wall to provide vertically-extending

air channels between said walls, the blocks of said first-mentioned type of tiers having aligned notches in the ends thereof providing locking spaces between the ends of the blocks spaced outwardly from the furring strips receiving notches therein, and a plurality of metal members having enlarged head portions retained within said locking spaces and having leg portions extending inwardly between the ends of the blocks into anchoring engagement with said furring strips.

- 10 2. The building structure of claim 1 which is characterized by the further fact that the blocks in said first-mentioned type of tiers have inner faces recessed between the notched ends thereof to provide vertically-extending air spaces, and the blocks in the other type of 15 said tiers having raised central portions on the inner faces thereof, said raised central portions providing vertically-extending air spaces on each side thereof in alignment with said first-mentioned air spaces, thereby providing vertically-extending air channels between said walls.
- 15 3. In a building structure, superposed tiers of building blocks providing an outer wall in which the blocks therein are staggered horizontally for adjacent tiers and aligned vertically for alternate tiers, said tiers being of two types alternately arranged within said wall, one 20 type of said alternate tiers being composed of blocks having vertically-extending notches at their inner ends forming enlarged spaces between the ends of the blocks for receiving furring strips extending vertically along the side face of said outer wall, the other type of said 25 tiers being composed of blocks having vertically-extending recesses located intermediately in the inner faces of the blocks and providing furring strip receiving channels vertically aligned with said enlarged spaces, furring strips received within said recesses and said enlarged spaces so as to 30 extend vertically along the inner face of an inner wall carried by said furring strips, at least some of said tiers of blocks being provided with means for anchoring said furring strips to said outer wall, said means for anchoring said furring strips to said outer wall comprising aligned notches in the ends of the blocks of said 35 first-mentioned type of tiers, said aligned notches providing locking spaces between the ends of the blocks so equipped, said locking spaces being spaced outwardly from the furring strip-receiving notches therein, and a plurality of metal members having head portions retained within said locking spaces and having leg portions extending inwardly into anchoring engagement with said 40 furring strips.
- 40 45
